UNITED STATES PATENT OFFICE.

EDWARD L. DELANY, OF BROOKLYN, NEW YORK, ASSIGNOR TO DELANY REALTY CORPORATION, OF BROOKLYN, NEW YORK.

FLUSH-TANK-OPERATING LEVER.

Application filed July 3, 1925. Serial No. 41,354.

My invention relates to improvements in flush tank operating levers.

The object of my invention is to provide a flush tank operating lever which can be readily attached and removed from the flush tank, and in which a substantial fulcrum is formed for the operating handle and at the same time providing means whereby the several parts can be readily assembled in the flush tank, and removed therefrom for replacing any worn parts thereof.

Another object of my invention is to provide a flush tank operating lever of this character in which the operating handle has the proper throw to move the flush valve a sufficient leverage to enable the same to be operated by less pressure and thus greatly reducing the wear and tear on the same, and all parts operated thereby.

20 A further object of my invention is to provide a simple, cheap and effective flush tank operating lever having certain details of structure and combination of parts hereinafter more fully set forth.

25 In the accompanying drawings:—

Figure 1 is a horizontal sectional view of the front wall of the flush tank showing my improved operating lever applied thereto.

Figure 2 is a vertical sectional view taken 30 on the line 2—2 of Figure 1.

Figure 3 is a transverse sectional view taken on the line 3—3 of Figure 1.

Referring now to the drawings, 1 represents the improved flush tank which is preferably made of enamel ware and is provided with an opening 2, arranged in the front wall thereof, and said opening in the present invention is preferably made of a rectangular form having rounded corners through which 40 passes a correspondingly shaped tubular member 3 having a flange 4 at its outer end and adapted to engage the outer face of the front wall of the tank. The corners 5 of the tubular member are preferably threaded at 6, upon which is screwed the nut 7, whereby the tubular member is firmly locked to the front wall of the tank and yet can be readily removed.

The inner end of the tubular member 3 50 has its two vertical side walls 8 and 9 provided with slots 10 and 11 which extend from the outer end a considerable distance as shown in Figure 1 of the drawings. The operating lever comprises an L shaped rod 12 fitting within the slots 10 and 11 and

adapted to rock therein and held in the inner end of said slots by a cap 13 surrounding the outer end of the tubular member beyond the lever, and said cap is held on the tubular member by means of a rivet 60 or cotter pin 14, whereby it can be readily removed. The L shaped operating lever 12 is provided with a projection 15 having a screw threaded opening 16 therein into which is screwed the operating lever 17. 65 The outer end of the operating lever is threaded as indicated at 19 in which may be screwed the handle or knob of any desired form.

The outer end of the cap 13 is provided 70 with a rivet 21 upon which is pivotally mounted the flush valve lever 22 which as is understood extends to a point above the flush valve and has the flush valve rod connected thereto. The lever 22 has an opening 75 23 through which the laterally turned end 24 of the lever 12 passes so that when the lever 12 is rocked in the slots 10 and 11 in the tubular member, the end 24 is raised, carrying with it the flush valve lever 22, 80 whereby the flush valve is raised from its seat, all of which is well understood and needs no further description.

While I have shown and described several 85 details of structure it will be understood that I do not care to limit myself to these details as the invention resides in providing a larger 90 fulcrum for the operating handle and one which has no permanent connection with the tubular member, whereby there is less liability of breakage and also provides a simple 95 construction whereby any of the parts can be readily replaced should they become worn. While I have shown the member 3 as angular it will be understood that the 100 same could be made cylindrical and in which event the flange 4 on its inner face would be provided with an angular projection to fit the opening to prevent the turning thereof in the angular opening 2 in the tank.

Having thus fully described my invention what I claim is:—

1. A flush valve operating mechanism, comprising a tubular member, an operating lever having trunnions mounted in slots carried by said tubular member, and means carried by said operating lever for operating the flush valve carrying lever.

2. A flush valve operating mechanism, comprising a tubular member adapted to be

clamped in an opening in the flush tank, and having oppositely arranged slots in its inner end, an operating lever having trunnions mounted in said slots, means for preventing the inward movement of said trunnions in the slots, and an arm carried by the lever and adapted to operate the flush valve carrying lever.

3. A flush valve operating mechanism, comprising a tubular member adapted to be secured in the front wall of the flush tank and having oppositely arranged slots in its side walls at their inner ends, an operating lever having trunnions mounted in said slots, a cap enclosing the end of said tubular member, means for holding the cap thereon, a flush valve carrying lever pivotally carried by the end of said cap, and an arm carried by the operating lever and adapted to raise the flush valve carrying lever.

4. A flush valve operating mechanism, comprising a tubular member adapted to pass through an opening in the flush tank, means for fastening said member in the opening, the inner end of said tubular member having its side walls provided with oppositely arranged slots, an operating lever having trunnions mounted in said slots, a cap surrounding the inner end of the tubular member and holding the trunnions in the slots, a flush valve operating lever mounted in the inner end of the cap, and an arm carried by the operating lever and adapted to engage the flush valve carrying lever for raising the same.

5. A flush valve operating mechanism, comprising a tubular member adapted to pass through an opening in the flush tank, means for locking said tubular member to the flush tank, the inner end of said tubular member having oppositely arranged slots, a lever having trunnions movable in said slots, a cap secured on the inner end of the tubular member and engaging the trunnions, a flush valve operating lever pivotally carried by the cap, and an arm carried by the operating lever and passing through an opening in the flush valve operating lever.

6. A flush valve operating mechanism, comprising a tubular member having a flange at its outer end adapted to engage the outer wall of the flush tank, a nut on said tubular member and adapted to engage the inner wall of the flush tank and lock the same to the flush tank, the inner end of the tubular member having oppositely arranged slots, an operating lever having trunnions mounted in said slots, a cap closing the end of the tubular member and en-

gaging the trunnions, a rivet carried by the end of the cap, a flush valve operating lever loosely mounted on the rivet, and an arm carried by the operating lever and engaging the flush valve operating lever for engaging the same when the lever is rocked downwardly.

7. A flush valve operating mechanism, comprising a tubular member adapted to be secured in an opening in the flush tank and having its inner end provided with oppositely arranged slots, an operating lever extending through said tubular member and having trunnions mounted in said slots, means for holding the trunnions in said slots, and means carried by the lever for engaging a flush valve operating lever, whereby the lever is raised when the operating lever is rocked downwardly.

8. A flush valve operating mechanism comprising a tubular member adapted to be secured in the side wall of the flush tank and having oppositely arranged slots extending from the inner end, an operating lever having trunnions mounted in said slots, a cap closing the end of the tubular member and adapted to hold the trunnions in the inner ends of the slots, a flush valve operating lever pivotally mounted on the cap, and an arm carried by the operating lever and adapted to engage the flush valve operating lever for raising the same when the operating lever is rocked downwardly.

9. A flush valve operating mechanism comprising a tubular member adapted to be secured in an opening in the flush valve tank, and having its inner end provided with oppositely arranged slots, and an operating lever extending through said tubular member and having trunnions mounted in said slots, means for holding the trunnions in said slots, a flush valve operating lever mounted on the tubular member, and means carried by the lever for operating the flush valve operating lever.

10. A flush valve operating mechanism comprising a tubular member adapted to be secured to an opening in the flush valve tank, and having its inner end provided with oppositely arranged slots, an operating lever extending through said tubular member and having trunnions mounted in said slots, means for holding the trunnions in said slots, a flush valve operating lever pivotally mounted on the tubular member, and means carried by the lever for operating the flush valve operating lever.

In testimony whereof, I have signed this specification.

EDWARD L. DELANY.
